UNITED STATES PATENT OFFICE.

JAMES E. HUTCHINSON, OF WASHINGTON, DISTRICT OF COLUMBIA, ASSIGNOR
TO THE WESTCOTT-JEWELL COMPANY, OF SENECA FALLS, NEW YORK.

DESIGN FOR A BOX OR HOLDER FOR BLOCKS, &c.

SPECIFICATION forming part of Design No. 26,318, dated November 24, 1896.

Application filed September 28, 1896. Serial No. 607,263. Term of patent 7 years.

To all whom it may concern:

Be it known that I, JAMES E. HUTCHINSON, of Washington, in the District of Columbia, have invented a certain new and original Design for Boxes or Holders for Kindergarten Spelling-Blocks; and I do hereby declare that the following is a full, clear, and exact description thereof, reference being had to the accompanying drawings, in which—

- 10 Figures 1 and 3 are perspective views of a box or holder embodying my design; and Figs. 2 and 4 are cross-sections, respectively, of the same.

The object of my invention is to produce a new and original design for a box or holder for kindergarten spelling-blocks; and to this end said invention consists in the design substantially as hereinafter specified and shown.

The leading feature of my design consists 20 in a rectangular box comprising a body and cover and parallel cleats on the outer surface of one of said parts.

In the embodiment of my design as illus-

trated there are placed upon the outer face or side of one section of the box or holder parallel cleats or strips A, that extend lengthwise thereof from end to end and are provided with overhanging inner edges. The outer edges of the cleats or strips are beveled. The box may be used for containing blocks or cards.

It will be apparent that attractive effects can be produced with my design by coloring the cleats or strips and the box-surface with different or contrasting colors.

Having thus described my invention, what I claim is—

The design for a box or holder for spelling-blocks, substantially as set forth.

In testimony that I claim the foregoing I have hereunto set my hand this 21st day of September, 1896.

JAS. E. HUTCHINSON.
